CONTROL DEVICE FOR INTERNAL COMBUSTION AND OTHER ENGINES

Original Filed March 19, 1926

UNITED STATES PATENT OFFICE

WARREN F. STANTON, OF PAWTUCKET, RHODE ISLAND

CONTROL DEVICE FOR INTERNAL COMBUSTION AND OTHER ENGINES

Application filed March 19, 1926, Serial No. 96,088. Renewed December 19, 1931.

Broadly stated the object of my invention is to utilize the conditions existing in an engine cylinder at different points of the piston stroke, as for example, the pressures therein, to control automatically any one or all of a number of factors which enter into the operation of the engine to the end that the highest efficiency thereof may be promoted and hand adjustment by the engine

operator be avoided or rendered unnecessary. to the engine cylinder pressure existing at such selected points and moved thereby in one direction, or the other dependent upon what is superior pressure at the selected points or not moved at all if there is no difference in pressure, and to utilize movements of the pressure actuated device so produced to control the timing of the spark, or other factors important to be controlled.

10 operator be avoided or rendered unnecessary. Thus, the timing of the spark, the mixture strength, the mixture temperature, and the density of the cylinder charge may be so controlled, and a feature of my 15 present invention is the control of all of these by one device. However, any one or any number of these may be the subject of automatic control in accordance with my invention. Control of the den-

100 sity of the cylinder charge is of practical importance, because it enables the construction of engines having higher compression than is now the practice with the advantages of the higher efficiencies and greater power 20 that result from high compression since the disagreeable knocking which occurs at low speeds of high compression engines is prevented and yet the full charge of gas at the higher speeds is assured.

25 My invention consists in whatever is described by or is included within the terms or scope of the appended claims.

In the accompanying drawing:

Fig. 1 is a view partly in side elevation and 35 partly in section of a four-cycle valve-in-head internal combustion engine embodying my invention;

Fig. 2 is a top plan view thereof with parts in section;

Fig. 3 is an end view partly in section;

Fig. 4 is a detail view on a larger scale of the rotary reciprocating valve;

Fig. 5 is a detail view in section of the dash-pot;

Fig. 6 is a bottom plan view thereof.

My invention is based upon and utilizes my conception of providing a pressure actuated device which may be a piston in a cylinder, which at selected points in the 50 stroke of the engine piston will be subjected

75 Outside the engine, 10, is mounted a cylinder, 12, within which is a piston, 13, which is connected with the timer, 14, of usual construction which by the movement of the piston, 13, is shifted to advance or retard ignition by changing the time of opening the circuit through the primary circuit of the spark coil. Each end of the cylinder, 12, is adapted 80 to be placed in communication with the combustion chamber, 15, to allow interchange or equalization of gas pressure upon either side 85 of the piston, 13, (according to which end of cylinder, 12, is placed in communication with the combustion chamber) with the pressure in the combustion chamber. If the pressure upon the piston, 13, is unbalanced, the 90 piston will move in the direction of the side of lower pressure.

Crank arm, 16, on the timer is pivoted to a rod, 17, and to the rod, 17, is pivoted a crank arm, 18, on a vertical shaft, 19, having within the cylinder, 12, an arm, 20, that is connected by a link, 21, to the piston, 13, and thus the timer is operatively connected with the control piston, 13.

The timer has some form of centrifugal 100

governor that acts to advance the spark with the increase of engine speed. This may be the ring type, 22, on a shaft, 23, connected by bevel gears, 24, to the cam shaft, 25, of the engine, and revolved at the same speed.

Regardless of what may be the action of the centrifugal advance, the automatic control by piston, 13, is effective since the latter acts on the timer body to turn the same.

- 10 By using a centrifugal controlled timer, set slightly late, designed to cover the wide open throttle range of action of any engine, a failure of the engine cylinder having the valve control hereinafter described (such as 15 a missing spark plug, or badly leaking valve, either of which would cause the control to go to full retard) will not affect the engine to as great an extent as without the centrifugal advance. Practically all cars in America 20 have the centrifugally controlled spark advance and due to the fact that hardly anyone moves the hand advance except at starting, the actual spark timing is late over 95% of the driving of the car, especially in the city 25 and town work. The driver will not have a knocking engine or advance the spark when he should, therefore practically all engines are being run with a late spark except when the throttle is wide open, at which time the 30 centrifugal automatic timer may give a correct timing of the spark at all speeds. The combination of automatic control and centrifugal advance partly overcomes the full retarding action that takes place with failure 35 of my valve-control automatic described hereinafter, when the control cylinder fails to function, by only retarding to the wide open throttle spark advance position at any speed. The engine thus equipped would perform as 40 well as do the cars now in use, even although my said valve control did not operate. This combination is not necessary at all except in the very highest grade cars, but might be used with cars already equipped with the 45 centrifugal advance.

I now describe the means for automatically placing the cylinder, 12, in communication with the engine combustion chamber, 15, premising that from opposite sides of the 50 piston, pipes or tubes, 26 and 27, respectively, lead from the cylinder to passages 28 and 29, respectively in the engine casting that have valve-controlled communication with such combustion chamber, and that specific valve 55 mechanism is one of the features of my invention. The valve, 30, of that mechanism is cylindrical with a tapered axial passage, 31, in direct communication with the combustion chamber of the engine, which has 60 an over-head cam-shaft, 25, driven at one-half crank-shaft speed by two-to-one gears, 33 and 34, that are driven from the engine crank-shaft (not shown). The engine shown, as I have said, is of the four-cycle, valve-in- 65 head type. The inlet and exhaust valves are

of a normal type common to over-head cam-shaft engines. The inlet valve, 35, is held closed by valve spring, 36, which holds the valve closed and it is opened by rocker-arm 37. The inlet-valve cam is 38. The exhaust-valve cam is 39, and 40 is the exhaust valve-stem guide. The exhaust-valve members are similar to the inlet valve members and are not shown completely.

The control valve, 30, is given a reciprocating and rotary or oscillating motion by eccentric, 41, that is mounted on shaft, 25, with its axis at an angle of twenty-two and one-half degrees to the cam shaft. This causes the eccentric to wobble through an angle of forty-five degrees for one complete revolution of the cam shaft and imparts the desired oscillating motion to valve, 30, at the same time it is reciprocating. A plate, 42, has a hub against which washer, 43, is held by cap screw, 44. Said plate forms one side of a groove in which shoes with pins, 45 and 46, ride. The position of eccentric, 41, can be adjusted by loosening the cap-screw, then turning the eccentric to the desired adjustment and then tightening the screw as it is held by the clamping action of said screw, in any desired adjustment. This means enables timing the control valve, 30. The eccentric, 41, is pivoted by the opposite pins, 45 and 46, in a yoke, 47, at the valve end. The yoke is pivoted by a pin, 48, to a block, 49, that is straddled by and pivoted to a fork, 50, on the valve end. It will be seen that a fully universal joint action takes place at either end of eccentric-rod or yoke, 47.

The eccentric, 41, is shown at its point of approximately maximum velocity for the valve, 30, on the downward stroke. The engine piston, P, is at top dead center on the beginning of the power stroke. Port, 51, in valve, 30, has just closed after passing the passage, 28, in the engine cylinder casting. Thus passage, 28, was in direct communication with combustion chamber, 15, for a short period just before dead center. Port, 52, will next be in communication with passage, 29, as valve, 30, descends and the engine piston, P, has traveled downward about one-tenth of its power stroke. Further downward movement of valve, 30, closes port, 29, and as the valve has been oscillated nearly forty-five degrees before the ports, 52 and 51, are again at a height to register with their respective passages, it will be seen that said ports and passages are only in communication on the downward stroke of valve, 30. Any desired timing for the opening of the ports may be obtained and the mechanism is positive and easily lubricated by oil collecting around the top of valve, 30, in the groove formed in the engine casting. Oil may be supplied from the engine pressure lubricating system by way of the hollow cam shaft 25. Oil is supplied under pressure to a

groove, 53, in cam shaft bearing block, 54, thence through passages, 55, 56 and 57, to the surfaces of eccentric, 41, where the excess lubricates the various joints and surfaces 5 of the control valve mechanism.

It will be seen that the valve, 30, has a very short passage, 31, between the engine combustion chamber and the valve ports, and this is important as a short passage gives the 10 most accurate control. It will be also seen that complete water cooling is assured for the valve and the passages, 28 and 29, which pass through the water space above the cylinder head.

15 Valve, 30, may be split so as to produce sealing of the ports by expansion of the valve under explosion pressure.

20 Ports may be arranged through the sleeves of Knight and other sleeve valve engines, so as to give the desired valve action without extra mechanism.

A cover, 58, encloses the valve mechanism and upon it is mounted the control cylinder 12.

25 Rod, 17, has a pointer, 59, showing by a scale, 60, on the instrument board of the car, its position at all times.

In starting the engine the operator pushes on the knob, 61, on the rod, 17, to close the 30 switch of the starting motor. The combination of starting switch and manual retarding of the spark control removes any danger or possibility of the automatic control being in an advanced position when the 35 starter motor is in operation. Many other arrangements can be devised to fit any particular requirements, such as a linkage to retard control, operating when a foot operated starting switch is used.

40 The starting switch at the end of rod, 17, consists of laminated contact, 62, insulated from rod, 17, which closes the circuit by making contact with blocks, 63 and 63, insulated from other parts by block, 64, fastened to 45 engine cover, 58. A short stiff spring, 65, is provided to keep the circuit open except when sufficient force is applied to knob, 61, to push the rod. Starting battery is designated, 66, and the starting motor for the 50 engine is designated, 67.

55 Preferably a dash-pot is provided for the control piston, 13. I show a vane type of oil dash-pot as part of the control cylinder casting. The lower end of shaft, 19, is slotted and fitted with a vane, 68, that oscillates in the cylindrical opening, 69, at the base of cylinder, 14. A cover closes this opening, 69, to retain oil. The cover has two integral vanes, 70 and 71. All parts are fitted 60 with close clearances to give the desired dash action. A filler screw, 72, is provided for the reservoir, 73, which holds a small reserve of oil for the dash chamber, 69. Both, 73 and 69 must be filled at the start.

65 Giving a description of the operation of the

mechanism shown in the drawing without repeating the detailed description of parts which has already been given, it will be understood that through the passages between the engine cylinder and the cylinder, 12, which include the 70 pipes, 26 and 27, pressure from the engine cylinder may be exerted on both sides of the piston, 13, the transfer of pressure between engine cylinder and cylinder, 12, being under control of the automatically operated valve, 75

30 no movement of the piston, 13, taking place if the pressure balances on opposite sides thereof, and movement in one direction or the other taking place when there is a difference of pressure upon opposite sides of the 80 piston, 13, and when movement of the piston, 13, takes place, the spark is advanced or retarded by the rotation of the timer by means of the connections between it and the piston, 13.

By way of illustration, when the engine 85 piston, P, has moved from dead center position through, say one-tenth of its power stroke, the valve, 30, will be moved to open communication between the combustion chamber and the cylinder, 12, on opposite 90 sides of its piston, 13. If ignition is delayed or occurs late after the power stroke movement of the engine piston begins, the rapid increase in explosion pressure which takes place will cause a superior pressure upon that side of the piston, 13, to the pressure upon the opposite sides which resulted from and exists in consequence of the pressure taken from the combustion chamber at the time the engine piston was in its dead center position and the 95 result will be that the piston, 13, will be moved in the direction to adjust the timer to advance the spark. When the spark is too early a corresponding but opposite action of the piston, 13, will take place and in consequence the timer will be adjusted by the movement of the piston, 13, to retard the spark. By the automatic change of the point of ignition according to the pressure conditions in the engine a state of equilibrium is reached when 100 the pressures at the dead center position of the engine piston on its compression stroke and when it traverses one tenth of its power stroke are substantially equal.

What I claim is:

1. The combination of an engine having a cylinder and a piston, a pressure operated means subjected to pressure within the cylinder at a predetermined point in the travel of the piston, ignition means including a timer, 115 an operative connection between said pressure operated means and the timer, a reciprocating and oscillating valve to control communication between the engine cylinder and said pressure-operated means, and automatic 120 means for actuating said valve.

2. The combination of a power producing engine having a power cylinder and a piston, pressure-operated means, means to cause the 125 operation of said pressure-operated means by 130

the differential of two pressures, one of which pressures is obtained from the engine at a predetermined point in the travel of the engine piston and means to utilize movement of said pressure-operated means for some purpose in the operation of the engine, comprising a reciprocating and oscillating valve.

3. A construction as in claim 2 in which the valve has an axial passage and ports opening thereto.

10 4. A construction as in claim 2 in which the engine is a valve-in-head type, has an overhead cam shaft, and the valve is operatively connected with said shaft.

15 5. An internal combustion engine having ignition means capable of variation of the time of igniting the charge and having an automatic ignition timer, means subjected to two pressures at predetermined points within the engine cylinder and a manual ignition timer.

20 6. The combination of a timer having a centrifugal ignition advance, means subjected to two pressures at predetermined points within the engine cylinder, comprising a piston and cylinder and means actuated thereby, and means for causing the action of the piston by pressure taken from the engine.

25 7. The combination of a timer having a centrifugal ignition advance and another ignition timer, and means subjected to two pressures at predetermined points within the engine cylinder.

30 In testimony whereof I hereunto affix my
35 signature.

WARREN F. STANTON.
